[57] CLAIM

The ornamental design for a hand-held remote control, as shown and described.

DESCRIPTION

FIG. 1 is a perspective view of the top, rear and left side of a hand-held remote control, according to the new design;

FIG. 2 is a top elevation view thereof;

FIG. 3 is a bottom plan view thereof;

FIG. 4 is a right side elevation view thereof with the left side being a mirror image thereof;

FIG. 5 is a front view thereof; and,

FIG. 6 is a rear view thereof.

The broken line showing of the buttons is for illustrative purposes only, and forms no part of the claimed design.
